UNITED STATES PATENT OFFICE

143,328

DESIGN FOR A BRACELET

George J. Lederer, Providence, R. I., assignor to Providence Stock Company, Providence, R. I., a corporation of Rhode Island

Application July 16, 1945, Serial No. 120,731

Term of patent 3½ years

(Cl. D45—4)

To all whom it may concern:

Be it known that I, George J. Lederer, a citizen of the United States, residing at Providence, in the county of Providence and State of Rhode Island, have invented a new, original, and ornamental Design for a Bracelet, of which the following is a specification, reference being had to the accompanying drawing, forming part thereof.

Fig. 1 is a plan view of a bracelet, showing my new design; and

Fig. 2 is a side view of the same.

I claim:

The ornamental design for a bracelet, as shown.

GEO. J. LEDERER.
